UNITED STATES PATENT OFFICE.

GIDEON JULIAN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-TRIMMING MACHINE.

1,275,564.

Specification of Letters Patent. Patented Aug. 13, 1918.

Application filed November 5, 1917. Serial No. 200,291.

To all whom it may concern:

Be it known that I, GIDEON JULIAN, a citizen of the United States, residing at Beverly, in the county of Essex and State of Massachusetts, have invented certain new and useful Improvements in Sole-Trimming Machines; and I do hereby declare the following to be a full, clear, and exact description of the invention, such as will enable others skilled in the art to which it appertains to make and use the same.

This invention relates to sole trimming machines and more particularly to that class of sole trimming machines for performing what is known as the "sole rounding operation" on block soles before attachment to the shoe. For purposes of illustration the improvement, forming the subject matter of the present application, is shown as applied to that type of sole rounding machine shown and described in Letters Patent of the United States to C. L. Allen, No. 881,994, and to B. F. Mayo, No. 882,009, both dated March 17, 1908, known as the "Planet sole rounder".

Machines of the Planet sole rounder type may be used for rounding or trimming either leather or rubber soles. In leather sole work the rounding knife is so formed as to produce a sole edge lying in a plane at right angles to the sole faces. In rubber sole work the rounding knife is so formed as to produce a beveled sole edge. The trimmed string in leather sole work readily falls away from the sole, but the trimmed string in rubber sole work tends to remain in place on the beveled edge of the sole and generally must be removed by the operator. The machine operates at such a high speed that the operators are frequently cut on the fingers when attempting to pick up the string, because their hands, inadvertently, will be caught by the knife as it swings around the sole.

One object of the present invention is to provide a safety device, for machines of the character indicated, which will prevent injury to the operator's hands by cuts from the trimming knife. In accordance with this object a feature of the invention comprises a guard for the trimming knife so arranged that it will prevent the operator from picking up the beveled string from in front of the rounding knife, and will also prevent

the knife from cutting the operator's fingers when coming from behind.

This and other objects of the invention will be understood from the following description of the features and combinations of parts through which said objects are attained, the novel features of said constructions being particularly pointed out in the appended claims.

The preferred form of the improvements, as applied to a sole rounding machine of the type described in said Allen and Mayo patents, is shown in the accompanying drawings, in which; Figure 1 is a plan view of a Planet sole rounder just starting a trimming cut, taken on a plane through the clamp supports, and having the present improvements incorporated therein; Fig. 2 is a detail, in plan, of the improved knife arm in cutting position against the pattern; Fig. 3 is a similar detail showing the angular position of the knife holder at the completion of a rounding operation; Fig. 4 is a detail of the rounding knife; and Fig. 5 is an elevation of the pattern, clamp, and knife holder at the commencement of the rounding operation.

The general mode of operation of the illustrated machine is identical with that of the Planet sole rounder fully described in said prior patents. The machine also includes mechanism for imparting an excess of travel, or overrun, to the knife beyond its starting point which is the same as described in the present inventor's prior Patent No. 540,062, dated May 28, 1895. As in the machine of said prior patents, the pattern 6 is supported on two posts rising from the usual cam plate 8 sustained on a rotary table 10; and a sole S is clamped on the pattern by a bevel edged clamping plate 12, sustained on two supports depending from a clamp carrier held in the usual overhanging portion of the frame (not shown). The rounding knife 14, which for rounding rubber or "rag" soles is bent at an angle to its shank and to the plane of the pattern, as shown in Fig. 4, is secured to a holder 16 pivotally mounted on a pin 18 (Fig. 5) in the end of an arm 20 rigidly secured to a segmental shaped plate 22, pivotally mounted at 24 in a carrier 26 (Fig. 1). The carrier 26 is mounted to slide inwardly and outwardly on a guide 28 on the table 10. A hand lever

30 tensions a spring within a drum 32 to withdraw the knife arm 20 from the pattern 6. The trimming cut is made by transferring the knife 14 around the pattern through 5 rotation of the table 10, the cam plate 8, sliding carrier 26 and spring within the drum 32 combining in their action to maintain the knife holder 16 in proper cutting position. All of the parts just described are 10 of the same construction and have the same mode of operation as in the machine described in said prior patents, a one-revolution clutch being thrown in by the operator for each new sole clamped on the pattern.

15 In the embodiment of the invention illustrated in the drawings the knife arm 20 carries a hollow post 34 (Fig. 5), the bore of which receives a pivot pin 36 depending from the rear end of a guard plate 38 extending 20 forwardly along the arm in a plane above the knife 14. The pin 36 has a flattened surface which is engaged, when the knife is in working position, as in Fig. 2, by a spring pressed latching bolt 40 housed 25 in a hollow lug 42 projecting laterally from the post 34. As shown in Figs. 1 and 2, the guard plate 38 completely covers the knife 14 and, since it is held in such position by the latch bolt 40, prevents the operator's fingers from being caught and cut by the knife, should he inadvertently bring his hand down on, or in advance of, the knife 30 in attempting to pick up the beveled string being trimmed from the sole.

35 As best shown in Fig. 2, the forward end of the guard plate 38 projects over the beveled edge of the sole clamping plate 14 and it must be withdrawn from such position before the clamp can be raised to release the 40 sole. The return movement of the knife after the usual period of overrun, is utilized to effect the operation. The pivoted knife holder has projecting outwardly from its lower end a crank arm 44 which carries a 45 depending lug, preferably a roll 46. On the upper face of the cam plate 8 is a stop in the form of a leaf spring held to the plate by screws at its rear end (Fig. 1) and having an upwardly-rising, yielding forward 50 end 48 (Fig. 5) located in both the path and plane of travel of the roll 46. On the forward movement of the knife 14 the spring 48 yields downwardly as the roll 48 travels over it, but on the backward movement of the knife, after the overrun, the roll engages the forward end of the spring and, as the knife continues to move backward, slides outwardly along it, turning the 55 knife holder 16 about its pivot 18 on the knife arm 20. The guard plate 38 is provided with a depending tab 50 (Fig. 5) at the heel of the knife, which is engaged by the knife as it turns with its holder. The pressure of the knife on the tab 50 overcomes 60 the force of the spring which urges

the latch bolt 40 forward, causing the guard plate to be carried outwardly with the knife to a position outside of the edge of the sole clamp 12, as shown in Fig. 3.

In addition to swinging the guard plate 70 away from the sole clamp the roll 46 and spring 48 also perform the function of setting the knife 14 at a proper angle for cutting diagonally into the sole margin on starting the cut on a new sole, all as described 75 and claimed in the patent to E. L. Hurd, No. 1,109,842, dated September 8, 1914, which illustrates a different construction.

The guard plate 38 may, at any time, be 80 turned back from above the knife 14 when it is desired to adjust or replace the knife, for outward pressure on the guard will cause the flat face on its pivot pin 36 to press back the latch bolt 40 and permit free turning movement on the pivot. The beveled string 85 removed by the angularly bent knife 14 is shown at T in Figs. 4 and 5.

The nature and scope of the invention having been indicated and the preferred form of the invention having been specifically described, what is claimed as new is:—

1. In a sole trimming machine, the combination with a pattern and means for clamping a sole thereon, a knife arm having a knife mounted thereon, and means for 95 transferring the point of operation of the knife around the pattern, of a guard plate sustained on the knife arm and extending over the knife.

2. In a sole trimming machine, the combination with means for clamping a sole, and a knife having a blade positioned to trim a string from the margin of a sole in the clamp, of a guard plate lying above the knife and having a tab depending adjacent 105 the heel of the knife.

3. In a sole trimming machine, the combination with means for clamping a sole, a knife support having a knife for trimming a string from the margin of the sole in the 110 clamp, and a guard plate pivotally mounted on the support and yieldingly held in position above the knife.

4. In a sole trimming machine of the type in which the sole is clamped on a pattern 115 and the point of operation of the knife is transferred around the pattern with an overrun and return therefrom at the completion of the trimming cut, the combination with said knife of a pivotally mounted guard plate 120 above the knife, and means controlled by the return from the overrun for swinging the guard plate away from the pattern.

5. In a sole trimming machine, the combination with a sole pattern, a knife arm, 125 and a swinging knife holder thereon carrying a knife, of a guard plate movably mounted on the arm, and means on the guard plate adapted to be engaged by the knife when its holder swings away from the pattern and 130

cause the guard plate to move with the holder.

6. In a sole trimming machine of the type in which a knife is guided by a pattern and is caused to traverse the outline of the pattern, overrun and return to its starting point, the combination with a pivoted knife holder having a crank arm provided with a depending lug, and a stop arranged in the path 10 of movement of said lug adapted to yield on the forward movement of the knife there-over and be engaged by the lug on the return of the knife from the overrun, whereby the knife holder is turned on its pivot to a position 15 with the knife blade at an angle to the outline of the pattern.

7. In a sole trimming machine, the com-

bination with a pattern and means for clamping a sole thereon, a knife arm having a knife holder pivoted thereon and depending below the pattern, and means for causing the knife to traverse the outline of the pattern, of a crank arm on said holder by which the knife may be turned to a position with its blade at an angle to the outline 20 of the pattern, and a leaf spring supported in the path of travel of the crank arm on the knife holder, the end of which yields as the crank arm passes over it in one direction of travel of the knife and acts as a stop, to 25 turn the knife holder, in the opposite direction of travel.

GIDEON JULIAN.
